SHOE LAST

Malcolm S. Cate, Watertown, Mass., assignor to
Hood Rubber Company, Inc., Watertown, Mass.,
a corporation of Delaware

Application April 8, 1935, Serial No. 15,186

5 Claims. (Cl. 12—135)

This invention relates to lasts of the type used in building shoes.

The principal objects of the invention are to provide for changing the form of the last to facilitate removal of the shoe without entirely disassembling the last, and to provide an efficient locking device therefor.

Other objects will appear from the following description and the accompanying drawing.

10 Of the drawing:

Fig. 1 is a side elevation of the assembled last, in its preferred form, parts being broken away to show the locking mechanism.

15 Fig. 2 is a similar view, showing the last in its shortened condition.

Fig. 3 is a sectional, detail view taken on line 3—3 of Fig. 1, showing the locking mechanism, parts being shown in section, and parts being broken away.

20 Fig. 4 is a view looking at the attaching face of the rear portion of the last as indicated by line 4—4 of Fig. 2.

Fig. 5 is a perspective view of the forward part of the last, showing the attaching face of this part.

25 Referring to the drawing, the last may be formed of wood, metal, or other rigid material, and comprises a front portion 10 and a rear portion 11, slidably joined along a plane lying at an angle acute to the sole of the last, and inclined forward at the top of the last.

In order to provide for sliding engagement of the last parts, one of the parts, preferably the front portion 10, is formed, on its attaching face 35 12, with a rib 13, of T form in cross section. The other part is formed with a T-groove 14 for sliding engagement with rib 13.

In order to provide against accidental separation of the parts of the last, a screw 15 is inserted 40 in the last part 11, with its head projecting into the groove 14, near the sole, and a clearance groove 16, for receiving the screw head, is formed in the face of the rib 13, to the extent of the desired motion.

45 To provide for locking of the parts, an opening 17, preferably circular in shape, is formed through the last part 11, extending cross-wise of the last, and intersecting the T-slot 14. A recess 18, constituting a continuation of the opening 17, when the last parts are assembled, is formed in the edge of the rib 13, and a locking pin 19, 50 slidably mounted in the opening 17, and having a clearance notch 20 in its side, is adapted to engage the notch 18. The locking pin 19, when engaged in the notch 18, holds the last parts

in locked engagement, but may be moved endwise to cause the notch 20 to permit sliding of the last parts upon each other. The ends of the pin 19, when it is engaged in the notch 18, are contoured to the contour of the faces of the last. A coil spring 21, located in a recess 22, in last part 11, engages the locking pin 19, and urges it in a direction to lock the parts.

The parting line between the last parts is such that it extends above the top of the shoe to be 10 constructed upon the last. When the shoe is completed, the locking pin 19 is pressed in a direction to release the parts, and the rear portion of the last is raised to the acute angle defined by the parting line, thereby shortening the last in its 15 greatest dimension, and permitting removal of the shoe. As the screw 15 limits such motion, the last parts are not entirely separated, and further raising of the rear part 11 causes part 10 to be withdrawn from the shoe. The relation of the last parts to each other, permitting limited adjustment, but preventing accidental separation, assures mating of the last parts.

20 I claim:

1. A shoe-building last comprising a toe portion and a heel portion, means including an interlocking rail and groove for slidably engaging the toe and heel portions with each other, and means for locking the portions in their assembled relation, said means comprising a passage formed crosswise through one portion of the last and intersecting said groove, a plug slidably mounted in said passage, a notch in said rail in alignment with the passage and engaged by said plug when the ends of the plug are flush with the surface of the last, said plug being formed with a notch to provide clearance for sliding said rail when the plug is released from the notch, and a spring for holding the plug and rail in locked position.

2. A shoe-building last as defined by claim 1 in which the ends of the plug are contoured to conform to the surface of the last adjacent the passage.

3. A shoe-building last comprising a toe portion and a heel portion, means including an interlocking rail and groove for slidably engaging the toe and heel portions with each other along a plane acute to the sole of the last and inclined forward toward the top of the last, and means for locking the portions in their assembled relation, said means comprising a passage formed crosswise through one portion of the last and intersecting said groove, a plug slidably mounted in said passage, a notch in said rail in alignment

with the passage and engaging by said plug when the ends of the plug are flush with the surface of the last, said plug being formed with a notch to provide clearance for sliding said rail when the plug is released from the notch and a spring for holding the plug and rail in locked position.

4. A shoe-building last comprising a toe portion and a heel portion slidably engaging each other, and means for holding the portions in their assembled relation, said means comprising a passage formed crosswise through the structure and a plug slideable in said passage transversely of the last and engageable with the last portions said plug having its ends contoured to

conform to the surface of the last adjacent the passage.

5. A shoe-building last comprising a toe portion and a heel portion slidably engaging each other, and means for releasably holding the portions in their assembled relation, said means comprising a passage formed crosswise in the structure and a plug slideable in said passage transversely of the last from a position of release in which the end of the plug projects from the last to a holding position in which the end of the plug by a contoured form hereof lies substantially flush with the surface of the last.
